UNITED STATES PATENT OFFICE

2,520,499

ROOF

Charles Léon Golaz, Tamatave, Madagascar

Application November 16, 1948, Serial No. 60,199
In France November 24, 1947

14 Claims. (Cl. 108—13)

1

The present invention relates to roofs, and in particular metallic roofs for colonial buildings.

My invention is concerned with roofs of the kind described in my prior U. S. applications Ser. No. 705,280, filed Oct. 24, 1946, for "Roofings." Its object is to provide improvements in such roofs.

Preferred embodiments of my invention will be hereinafter described with reference to the accompanying drawings, given merely by way of example, and in which:

Fig. 1 is a perspective view of a portion of a roof made according to the present invention, the covering elements being removed on the right-hand side of this figure, so as to show the framework;

Fig. 2 is a perspective view of a tile of the roof covering shown by Fig. 1;

Fig. 3 also shows in perspective view a tile made according to a modification;

Fig. 4 is a longitudinal section of the roof of Fig. 1, on the line IV—IV of this figure;

Fig. 5 is a longitudinal section on the line V—V of Fig. 1;

Fig. 6 is a transverse section on the line VI—VI of Fig. 1;

Fig. 7 shows, in cross section, the detail of assembly of two adjoining tiles on a frame-work element;

Fig. 8 illustrates the same detail in the case of tiles made according to the modification of Fig. 3;

Figs. 9 to 11 are transverse sections showing three modifications of the same detail of assembly;

Fig. 12 shows, in transverse section, the detail of the assembly of a tile with a hip-rafter;

Fig. 13 is a longitudinal section of a particular assembly of two successive tiles;

Fig. 14 is a transverse section of a roof covered with concave flanged tiles and convex flanged tiles;

Fig. 15 illustrates, still in transverse section, another embodiment of a structure as disclosed by Fig. 14;

Fig. 16 shows, in longitudinal section, a particular system of assembly of the tiles on the purlins of the framework, this system being intended to ensure perfect safety;

Fig. 17 is a view similar to Fig. 1 illustrating still another embodiment of my invention;

Figs. 18 and 19 show, in section parallel to the slope of the roof, two systems for securing the covering elements;

Finally, Fig. 20 is a section on the line XX—XX of Fig. 19.

2

The framework of the roof, in the embodiments hereinafter described, includes rafters 2 supporting transverse purlins 3.

This framework is covered with a plurality of elements 4 called, in the present description, tiles although they differ in many points from conventional tiles.

As already described in my prior patent above referred to, these tiles are disposed to make each an angle (preferably approximately the same for all of them) with the general direction of rafters 2, so that the whole constitutes a succession of steps. Each step corresponds to the interval between two successive purlins 3 and fixation means 5 (for instance nails or screws) extending in a direction substantially parallel to the general slope of the roof secure the tiles to the framework (for instance to the lower side wall of purlins 3).

For this purpose, each tile is advantageously made of rectangular shape, with upper and lower sides bent at right angles, one downwardly and the other upwardly, to form flanges 4⁰ and 4⁰⁰. The upper flange 4⁰⁰ of a tile is applied against the lower side wall of a purlin and is covered by the lower flange 4⁰ of the tile located immediately above.

Such tiles may be made of any suitable material, such as clay, fibro-cement, etc., but preferably, for roofings of tropical buildings, they are made of sheet metal, the main portion of the tile being preferably plane.

According to a feature of the present invention, each tile, made, in a general manner, as above described, is provided with lateral upward flanges 4a, preferably of smaller height than flanges 4⁰ and 4⁰⁰.

With such an arrangement, supposing that two adjacent tiles are separated from each other by a rod 16 supported by purlins 3, the flanges 4a of the two respective tiles applied against the sides of said rod 16 will be covered by means of an arch-shaped cover 17 adapted to span the whole of rod 16 and said two flanges 4a.

Advantageously, each cover 17 includes, in addition to its lateral flanges 17a, a lower flange 17⁰ and an upper flange 17⁰⁰.

Lateral flanges 17a are advantageously of a height corresponding substantially to that of rods 16 and flanges 17⁰ and 17⁰⁰ are made of a height approximately equal to the sum of the heights of a purlin 3 and a rod 16, the flanges 4⁰ and 4⁰⁰ of tiles 4 being then made of a height corresponding to that of a purlin 3 whereas their

flanges $4a$ are made of a height corresponding to that of said rods 16 .

It is pointed out that, in order to facilitate transportation and storing of the tiles, the flanges of said tiles may be bent at an obtuse angle to the main part thereof, as shown by Fig. 3.

In this case, of course, rods 16 and covers 17 will be made of trapezoidal section.

With an arrangement as above described, the tiles, fixed on their four sides on the framework, are assembled in a perfectly watertight manner. At every point of its outline, each tile is protected against rain or wind infiltration since, along its lateral sides, it is covered by a cover 17 , at the top it is covered by the overlapping lower flange of the tile located above it, whereas, at the bottom it is bent downwardly to cover the upper flange of the tile located under it.

This structure does not include any part driven perpendicularly to the general surface of the roof and therefore no infiltration can take place at the points of fixation.

On the other hand, as the tiles are each fixed along its four sides, it is possible to make use of longer tiles which involves a reduction of the costs for covering a given area. Finally, due to their lateral fixation on rods 16 , the tiles are less liable to vibrations of the kind of those which may occur when a violent wind is acting on an ordinary sheet metal roof covering.

Concerning the connection of the covering with the ridge-piece, it will be effected in the same manner as described in my above mentioned prior patent application, i. e. by providing, if necessary, between the lower flanges of the tiles of the last row at the top and the purlin located immediately below the ridge-piece, a thickness piece capable of compensating for the excess of length of said tiles with respect to the height of the strip that remains to be covered.

As for the covering of the width of a roof slope, it will suffice, if this width does not constitute a true multiple of the width of the tiles, to reduce the width of the tile resting on the ridge piece (if such a piece exists) and then to form a new flange on this side of the tile.

In the particular case of roof surfaces of trapezoidal or triangular shape, the angle tiles must be cut to fit on the ridge pieces, suitable flanges being formed along the edges thus cut.

Figs. 4 to 7 are sectional views intended to illustrate the above stated features.

It has been supposed, in the preceding description, that the tiles were intended to be secured to a wood framework, but, according to my invention, these tiles can be used in the same manner in the case of a metallic framework in which wood rods 16 are replaced by structural beams such as $16a$.

For instance, when each rod is constituted by two L-shaped irons placed at a distance from each other and opposed in position (Fig. 9), I may engage the side flanges $4a$ of the tiles behind the inner faces of said irons and place cover 17 so that the flanges $17a$ thereof are applied against the outer faces of said irons $16a$.

If the rod is constituted by a single angle iron $16a$, as illustrated by Fig. 10, I may associate with said element a wood rod 16 about which is fitted cover 17 , transverse tie-rods 18 being advantageously provided to keep the various elements of the assembly tightly applied against one another.

If the rod is constituted by an inverted T iron,

as shown by Fig. 11, the lateral flanges $4a$ of the tiles may be applied against the respective sides of the vertical portion of said iron $16a$, the three thicknesses of metal thus juxtaposed being surrounded by cover 17 the branches $17a$ of which are at a distance from each other substantially equal to the total of these three thicknesses.

If, instead of metallic tiles, I make use of fibrocement or analogous tiles, a particular arrangement is to be used for connection of the tiles with a ridge piece, because, in this case, it is not possible, after having cut off a portion of the tile, to form a flange along the new edge. I may, for this purpose, make use of the arrangement of Fig. 12.

As shown by the drawing, I provide an independent flange piece or angle piece 19 one of the sides of which rests upon tile 4 whereas the other side bears against the ridge piece $16b$, a ridge-piece cover 17 surrounding the whole of said ridge-piece and the last mentioned side of piece 19 .

Advantageously, suitable means will be provided for fixing said piece 19 on purlins 3 and cementing means will be applied to prevent any infiltration of water between the lower wing of piece 19 and the tile 4 on which it rests.

However, this may be avoided by preliminarily providing, against the ridge piece $16b$, a piece $18b$, for instance of zinc, curved at its lower part so as to form a drain $180b$, whereby any water as may have leaked is evacuated through this kind of gutter $180b$.

Fig. 13 shows a particular embodiment of the invention according to which, instead of keeping the upper flanges of tiles 4 and covers 17 in contact with the lower flanges of the corresponding tiles and covers of the row located immediately above (case of Fig. 4), the tiles and covers are made substantially longer than the distance between purlins 3 , whereby a space may remain between the corresponding upper flanges 400 and the lower flanges 40 , each tile and cover thus extending slightly beyond (in the downward direction) the purlin 3 on which the corresponding element (tile or cover) is resting.

The interval between said flanges will then be filled by a small block 111 .

Furthermore, in order in particular to reduce the height of the respective flanges and also to reduce the load supported by each flange, the upper ends of tiles 4 may rest on a supporting wood block 112 , provided along every purlin on the lower side wall thereof.

It should be noted that block 111 will tend to prevent infiltrations of water between the two flanges located on opposite sides of said block. Fluidtightness of the assembly may be further improved by bending down the upper edge $4a^00$ of the upper flange 400 of the tile, as shown by Fig. 16. In this case, block 111 serves also to prevent crushing of this curved edge.

When purlin 3 is made of wood, it will be advantageously protected against moisture by a sheet of zinc or a similar material 113 applied against the lower side face of said purlin.

In order to simplify construction, I may replace the rod covers 17 above described by elements of greater width extending from one side of a rod 16 to the opposite side of the next rod 16 . Such elements then constitute convex flanged tiles alternating with the concave flanged tiles 4 above described. Such elements are shown by Figs. 14 and 15.

All these tiles may be provided with stiffening or reinforcing ribs.

As shown by Fig. 15, the convex tiles 114 may be of smaller width than the ordinary tiles 4.

Connection of the tiles with a ridge piece will take place as above indicated, the interval that may exist between the cooperating flanges which are closest to said ridge piece being filled by a block 115 (Fig. 15).

Figs. 17 to 20 show another embodiment of my invention according to which each rod 15 rests, at its upper end, directly upon the upper face of the corresponding upper purlin and, at its lower end, upon the upper end of the rod located in line with the above mentioned one and which bears directly upon the lower purlin. The three thicknesses constituted by the purlin and the two rods superposed thereto being assembled together for instance by means of a bolt 206.

With this arrangement, each tile can rest directly on the upper faces of the two purlins between which it extends, the lower flange 40 of said tile covering the upper flange 400 of the tile located immediately below.

It should be noted that the interval between two consecutive purlins is to be slightly smaller than the length of the tile so that the latter can rest upon said purlins. For instance, this interval will be chosen such that the upper end of each tile extends over substantially one fourth of the width of the purlin.

The tiles can then be fixed to the framework merely through parts 5a, such as nails, screws or rivets (in the case of metallic tiles) which secure the side flanges 4a of the tiles to rods 16. Advantageously, as above described, said rods are protected by covers 17 which extend over said side flanges 4a.

However, I may improve the fixation of the tiles to the framework by providing on the top face of every purlin 3, as shown by Fig. 18, a fixation block 201, against the downward face of which can be fixed, by means of nails or screws 202, the cooperating flanges of the tiles, a packing block 111 being advantageously interposed between said flanges.

This arrangement constitutes a considerable simplification over the prior devices.

Of course, this assembly can be adopted both for tiles with straight edges and for tiles with oblique edges. It is also applicable to the case of convex flanged tiles being substituted for covers 17 (case of Fig. 20).

When tiles 4 are of trapezoidal section (flanges oblique to the main portion of the tile) rods 16 are given a trapezoidal section as shown by Fig. 20.

It is then possible to make use, for wedging the tiles at their top angles, the steps r formed by the bases of the upper rods 16, which bases project beyond the edges of the upper faces of the lower rods 16.

To obtain this result, it will be of interest to have the upper rods corresponding downwardly beyond the purlin on which they are resting at their lower ends, as shown by Fig. 19, so that the length l over which steps r hold down the under tile is correspondingly increased.

Thus the tiles 4 will be secured in position without necessitating special fixation means, since their upper angles are engaged under steps r and the lower flanges 17b of covers 17 (or of the convex tiles that play the same part) prevent said tiles 4 from sliding down.

Of course, this arrangement does not exclude 75

the use of special means for fixing the tiles to rods 16 through lateral flanges 4a and to blocks 201 through their upper and lower flanges.

In a general manner, while I have, in the above description, disclosed what I deem to be practical and efficient embodiments of my invention, it should be well understood that I do not wish to be limited thereto as there might be changes made in the arrangement, disposition and form of the parts without departing from the principle of the present invention as comprehended within the scope of the accompanying claims.

What I claim is:

1. A roof which comprises, in combination, inclined rafters, interspaced purlins carried by said rafters transversely thereto, a plurality of rods, each interposed between two consecutive purlins, located in vertical planes parallel to the vertical planes of said rafters, said rods being mounted to make with a horizontal plane an angle smaller than the angle made with this plane by the rafters, a plurality of rectangular tiles of a width equal to the interval between two consecutive rods, each tile including a flat main part and flanges along the four sides thereof, the flanges along the upper and lateral sides of the tile extending upwardly and the flange along the lower side extending downwardly, said tiles being juxtaposed in rows, with their upper and lower flanges applied against the lower sides of said purlins, the lower flanges of each row covering the upper flanges of the row immediately below it, the lateral flanges of said tiles being applied along the respective sides of said rods, and a cover extending over each of said rods and provided with downward flanges covering the lateral flanges of the tiles located on either side of said rod.

2. A roof which comprises, in combination, inclined rafters, interspaced purlins carried by said rafters transversely thereto, a plurality of rods, each interposed between two consecutive purlins, located in vertical planes parallel to the vertical planes of said rafters, said rods being mounted to make with a horizontal plane an angle smaller than the angle made with this plane by the rafters, a plurality of rectangular tiles of a width equal to the interval between two consecutive rods, each tile including a flat main part and flanges along the four sides thereof, the flanges along the upper and lateral sides of the tile extending upwardly and the flange along the lower side extending downwardly, said tiles being juxtaposed in rows, with their upper and lower flanges applied against the lower sides of said purlins, the lower flanges of each row covering the upper flanges of the row immediately below it, the lateral flanges of said tiles being applied along the respective sides of said rods, and a cover extending over each of said rods and provided with downward flanges covering the lateral flanges of the tiles located on either side of said rod, said rods being disposed in lines parallel to the slope of the roof, said rod covers including each a downward flange at the lower end and an upward flange at the upper end and the lower flange of a rod cover covering the upper flange of the rod cover immediately below it.

3. A roof according to claim 1 further including means extending through said upper and lower flanges for fixing them to said purlins, said means being parallel to the slope of the roof.

4. A roof according to claim 1 further including means extending through said rod covers and the lateral flanges of said tiles for fixing them to

said rods, said means being parallel to the direction of the purlins.

5. A roof according to claim 1 further including means extending parallel to the slope of the roof, through said upper and lower flanges for fixing them to said purlins, and means parallel to the direction of said purlins extending through said rod covers and the lateral flanges of said tiles for fixing them to said tiles.

6. A roof according to claim 1 in which said flanges are at right angles to said flat part of the tile.

7. A roof according to claim 1 in which said flanges make obtuse angles with said flat part of the tile.

8. A roof according to claim 1 in which an interval is left between the upper flange of a tile and the lower flange of the next tile above it, a block being interposed between said two flanges.

9. A roof according to claim 1 in which an interval is left between the upper flange of a tile and the lower flange of the next tile above it, a block being interposed between said two flanges, the upper edge of said upper flange being curved downwardly.

10. A roof which comprises, in combination, inclined rafters, interspaced purlins carried by said rafters transversely thereto, a plurality of rods, each interposed between two consecutive purlins, located in vertical planes parallel to the vertical planes of said rafters, said rods being mounted to make with a horizontal plane an angle smaller than the angle made with this plane by the rafters, a first set of rectangular tiles of a width equal to the interval between two consecutive rods, each tile including a flat main part and flanges along the four sides thereof, the flanges along the upper and lateral sides of the tile extending upwardly and the flange along the lower side extending downwardly, a second set of rectangular tiles of a width equal to the interval between two consecutive rods, each tile of this second mentioned set including a flat main part and flanges along the four sides thereof, the flange along the upper side of the tile extending upwardly and the flanges along the lower and lateral sides extending downwardly, said tiles being juxtaposed in rows, so that the tiles of the first set alternate, in each row, with those of the second set, with their upper and lower flanges applied against the lower sides of said purlins, the lower flanges of each row covering the upper flanges of the row immediately below it, the lateral flanges of said tiles being applied along the opposite sides of consecutive rods, and covering one another.

11. A roof which comprises, in combination, inclined rafters, interspaced purlins carried by said rafters transversely thereto, a plurality of rods, each interposed between two consecutive purlins, located in line with one another in vertical planes parallel to the vertical planes of said rafters, the upper end of each of said rods resting directly on one purlin and the lower end thereof resting upon the upper end of the next rod located below it, so that each rod makes with a horizontal plane an angle smaller than the angle made with this plane by the rafters, a plurality of rectangular tiles of a width equal to the interval between two consecutive rods, each tile including a flat main part and flanges along the four sides thereof, the flanges along the upper and lateral sides of the tile extending upwardly and the flanges along the lower side extending down-

wardly, said tiles being juxtaposed in rows, with their upper and lower flanges located above said purlins, the lower flanges of each row covering the upper flanges of the row immediately below it, the lateral flanges of said tiles being applied along the respective sides of said rods, and a cover extending over each of said rods and provided with downward flanges covering the lateral flanges of the tiles located on either side of said rod.

12. A roof which comprises, in combination, inclined rafters, interspaced purlins carried by said rafters transversely thereto, a plurality of rods, each interposed between two consecutive purlins, located in line with one another in vertical planes parallel to the vertical planes of said rafters, the upper end of each of said rods resting directly on one purlin and the lower end thereof resting upon the upper end of the next rod located below it, so that each rod makes with a horizontal plane an angle smaller than the angle made with this plane by the rafters, a first set of rectangular tiles of a width equal to the interval between two consecutive rods, each tile including a flat main part and flanges along the four sides thereof, the flanges along the upper and lateral sides of the tile extending upwardly and the flange along the lower side extending downwardly, a second set of rectangular tiles of a width equal to the interval between two consecutive rods, each tile of this second mentioned set including a flat main part and flanges along the four sides thereof, the flange along the upper side of the tile extending upwardly and the flanges along the lower and lateral sides extending downwardly, said tiles being juxtaposed in rows, so that the tiles of the first set alternate, in each row with those of the second set, with their upper and lower flanges located above said purlins, the lower flanges of each row covering the upper flanges of the row immediately below it, the lateral flanges of said tiles being applied along the opposite sides of consecutive rods, and covering one another.

13. A roof according to claim 11 further including means parallel to the direction of the purlins extending through said rod covers and the lateral flanges of said tiles for fixing them to said rods.

14. A roof according to claim 12 in which said flanges make obtuse angles with the flat parts of the tiles, said rods having their under face wider than their upper face to accommodate the lateral flanges of the tiles, the upper ends of the lateral flanges of each tile being caught under the projecting under faces of the rods carrying the tile located immediately above.
